UNITED STATES PATENT OFFICE

2,311,891

ROAD GROOVING MACHINE

Harry Tyson, Brooklyn, N. Y.

Application April 17, 1941, Serial No. 388,941

8 Claims. (Cl. 262—20)

The invention relates to road grooving machines.

Due to weather conditions and large amounts of traffic, road pavements, particularly after having been laid for a while, will be worn smooth. This smoothness induces skidding of motor vehicles, thus setting up a serious traffic menace. Naturally this condition will be more evident and more dangerous on hills, sharp curves and road intersections.

The principal object of the present invention is to provide a machine that will efficiently cut a plurality of series of parallel grooves in the hardened surface of a road. These grooves are preferably disposed in angular relation to each other and thus a surface is provided which will greatly increase traction and help to eliminate skidding.

Numerous other objects and advantages will become apparent as this specification proceeds. Referring to the drawings forming a part thereof and in which one form of the invention is illustrated:

Fig. 1 is a top plan view;

Fig. 2 is a rear elevation, parts being broken out and parts being broken away for economy of space and simplicity of illustration;

Fig. 3 is a side elevation with parts broken away;

Fig. 4 is a fragmentary detail sectional view taken on the line 4—4 of Fig. 1;

Fig. 5 is a fragmentary detail sectional view taken on the line 5—5 of Fig. 4;

Fig. 6 is a fragmentary sectional plan view taken on the line 6—6 of Fig. 4;

Figs. 7 and 8 are fragmentary detail sectional views taken on the lines 7—7 and 8—8 respectively of Fig. 6;

Fig. 9 is a fragmentary detail sectional plan view taken on the line 9—9 of Fig. 2, showing one of the wheels in position to drive the machine in one direction;

Fig. 10 is a view similar to Fig. 9 showing the wheel swung around 90° so as to drive the machine in a direction at right angles to the direction it would be driven with the wheels in the position of Fig. 9;

Fig. 11 is an enlarged detail fragmentary sectional view taken on the line 11—11 of Fig. 10;

Fig. 12 is a fragmentary detail sectional view taken on the line 12—12 of Fig. 9;

Figs. 13 and 14 are fragmentary detail sectional views taken on the lines 13—13 and 14—14, respectively of Fig. 2; and

Figs. 15, 16 and 17 are diagrammatic plan views showing the operation of the machine.

The present invention has to do with the subject matter of and is a continuation in part of my copending application, Serial No. 324,772, filed March 19, 1940, now Patent No. 2,244,742, dated June 10, 1941.

Referring again to the drawings the reference numeral 20 designates the main frame which is rectangular in plan view and each of its members are preferably channel or U-shaped in cross section. A cross member 21 extends from side to side of the main frame and on this cross member and the forward portion of the main frame two motors 22 and 23 are supported.

The motor 22 drives the machine while it is functioning to cut the grooves in the roadway as will be hereinafter apparent. The motor 23 has for its main function to rotate the cutters. In addition, this motor is used to drive the machine in a direction at right angles to that in which it moves when cutting the grooves as will hereafter become apparent.

In cutting a series of grooves, particularly in concrete or cement, hard spots will always occur. If one attempts to synchronize the drive of the machine with the speed of rotation of the cutters, in a road surface where there are particularly few or no hard spots the speed and efficiency of the machine is greatly lowered as the cutters will be rotating without doing nearly the amount of work they might do. On the other hand if a series of particularly hard spots are struck the cutters will slide over the surface or cut the grooves only a fraction of the required depth.

In order to insure the proper functioning of the cutters regardless of the conditions of the roadway a hydraulic coupling or slip clutch 24 is interposed between the motor 23 and its drive shaft 25. Thus if the cutters are held back by road conditions the coupling or clutch 24 will slip and the movement of the machine will be sufficiently arrested to insure the proper functioning of the cutters. The construction of such hydraulic couplings or slip clutches is well known and it is not thought necessary to illustrate same in detail. The motor 22 is provided with the usual well-known transmission for forward and reverse movement.

The shaft 25 has universal joints 26 and 27, see Fig. 1, and has secured to its end remote from the motor 23 a bevel gear 28. The bevel gear 28 meshes another bevel gear 29 mounted on a shaft 30. Secured to the ends of shaft 30 are sprockets 31 over which sprocket chains 32 pass and engage sprockets 33 mounted on the wheel axles 34. Thus it will be apparent the rear wheels 35 are driven so as to cause the machine to move.

The shaft 30 is carried in bearings mounted on an auxiliary frame 36 which is rectangular in plan view and has downwardly extending legs 37 in the region of each of its corners. These legs are guided in yoke-shaped members 38 secured to the main frame 20 and carry the wheel axles 34 at their lower extremities.

Hydraulic jacks 39 are interposed between the

main frame 20 and the auxiliary frame 36. Suitable lines 40 connect the jacks to a main pressure cylinder 41. These connections are shown broken away at the jacks and the main pressure cylinder for simplicity of illustration. A pump for building up pressure in the cylinder 41 may be driven through the medium of a sprocket and sprocket chain drive 42 from the power shaft 25. With this arrangement the entire main frame may be raised or lowered in relation to the auxiliary frame and wheels.

As it will hereinafter becomes apparent the cutters are carried by the main frame. Thus when it is desired to move the machine after a series of grooves has been completed the main frame may be raised and the cutters withdrawn from the grooves. The relative movement between the main frame and the auxiliary frame also permits of setting the machine up to cut grooves of varying depths. In order to observe the amount of movement between the main frame and the auxiliary frame a graduated bar 43 is mounted on the main frame and a pointer 44 on the auxiliary frame.

In normal operation of the machine it is advantageous to have the cutters at the rear end of the machine. In roads where a curb or other obstruction occurs at the edge this would mean a very troublesome manipulation of the machine to complete the grooves. In order to overcome this difficulty, means are provided whereby the cutters may traverse the under side of the machine for practically its entire length and cut their grooves.

The operation of the cutters will now be described. The motor 23 has the conventional transmission mechanism of which the gear shift handle 45 is indicated in Figs. 1 and 3. The power shaft 46 has secured to it a sprocket 47 which is connected by a sprocket chain 48 with another sprocket 49 mounted on a shaft 50.

The shaft 50 rotates in suitable bearings, one or more of which may be mounted on a channel member 51 extending from end to end of the machine and suitably secured to the end members of the main frame 20. A pair of sprockets 52-52 are secured to the rear end of shaft 50 and sprocket chains 53-53 connect these sprockets with other sprockets 54-54 mounted on shafts 55-55. Two sets of cutting discs are utilized and as the drive for both is identical only one will be described.

A sub-frame 56 which may be box-like in construction is provided for each set of cutters and suitable bearings on the under side thereof carry the shafts 57 to which the cutters 58 are secured. Any number of cutters may be utilized and they may be spaced apart as desired. In cutting roadways for trenches a single pair of cutters spaced the proper distance apart will cut through the pavement so that it may be removed prior to digging the trench.

The shafts 54 pass through the boxes 56 and the boxes and cutters are movable lengthwise of the machine in relation to the shafts 54. The shafts 54 have splines 59 running their entire length and bevel gears 60 are splined on these shafts so as to permit of longitudinal movement while the shafts and gears are being rotated.

The bevel gears 60 mesh other bevel gears 61 which are secured to shafts 62 carried in the boxes 56. Sprockets 63 mounted on the shafts 62 through the medium of sprocket chains 64 passing over sprockets 65 secured to the shafts 57 drive these shafts and the cutters.

The side members of the frame 20 are provided

with guides 66 for the boxes 56 and other guides 67 are secured to the under side of the channel member 51 for the other sides of the boxes. Threaded shafts 68 pass through nuts 69 on the boxes and these shafts may be rotated by cranks 70 to move the boxes and the cutters in relation to the machine. Obviously a power take-off from either of the motors might be utilized for rotating the shafts 68.

As heretofore stated when the machine is functioning it is moving forwardly or rearwardly. However, when a series of grooves has been completed in order to prevent much troublesome manipulation of the machine it is moved laterally to bring it in position to cut the next series of grooves. For this purpose the wheels are mounted so they may be swung 90°. Fig. 9 shows one of wheels in the position it would assume with the machine being driven forwardly or rearwardly. Fig. 10 shows the wheel swung at 90° so the machine may be driven in a lateral direction.

When the machine is being driven forwardly or rearwardly through the sprocket and chain connections 31, 32, 33, the axles 34 are free to rotate in their bearings 71 secured to the lower ends of the legs 31. The axles 34 have extensions 72 and in this position the hubs of the wheels are secured by pins 73 to the extensions 72. As shown in Fig. 11 a plurality of openings 14 are provided for the pins 73 to facilitate the alignment of the hubs and extensions prior to entering the pins.

When it is desired to move the machine in a lateral direction the pins 73 are removed thus permitting the wheels to rotate freely on the extensions 72. The extensions 72 are pivoted at 75 in the axles 34 and a locking pin 76 holds the axles and extensions rigid while the machine is functioning. When the wheels are swung to the other position, the locking pins 76 are removed.

One of the rear wheels 35 and one of the front wheels 77 have internal gears 78. These internal gears 78 are meshed by pinions 79 secured to the ends of a shaft 80, mounted in the frame of the machine. The shaft 80 has a sprocket 81 mounted thereon and the sprocket 81 is driven by a sprocket chain 82 which passes over a sprocket 83 mounted on the shaft 84. The shaft 84 is in effect an extension from the power shaft 46, a clutch 85 being interposed between the shaft 84 and shaft 46 so that the shaft 84 is only driven when the clutch 85 is thrown. The shaft 84 is provided with a brake indicated at 86 in Figs. 1 and 3.

In order to prevent the cutters from becoming unduly heated they are supplied with water through nozzles 87. The nozzles 87 are connected to a pipe 88 which is carried by the box 56. Flexible connections 89 connect the pipes 88 to a tank 90 which is carried on cross members mounted on the auxiliary frame 36. An inlet 91 to the tank may be connected to a convenient hydrant or if water under pressure is not available, a pump 92 may be utilized to pump water from any source of supply into the tank.

Figs. 15, 16 and 17 show the operation of the machine, the machine being designated by the reference character A. In Fig. 15 it is assumed the machine is moving in the direction of the arrow B with the cutters in the rear end of the machine. The machine reaches the position of Fig. 15 and the cutters are then moved to traverse the under side of the machine and complete the grooves. The cutters are then withdrawn from the grooves in the manner heretofore

described, the wheels are turned and the machine is moved in the direction of the arrow C to the dotted line position of Fig. 16. The cutters are then placed in their operative position, the wheels are again turned and the machine is moved forward in the direction of the arrow D to the dotted line position of Fig. 17. The machine is then reversed and moves in the direction of the arrow E to complete the next series of grooves.

The machine may be utilized for other purposes than cutting grooves in roadways. For instance, slabs of granite or other analogous materials could be cut up in blocks for paving.

Numerous changes in details of construction and arrangements of parts may be made by one skilled in the art without departing from the spirit of the invention as set forth in the appended claims.

I claim:

1. A road grooving machine having in combination a main frame, sub-frames mounted on said main frame, means for moving each of said sub-frames from end to end of said main frame, a shaft extending from end to end of said machine for each of said sub-frames, means for rotating each of said shafts, other shafts mounted for rotation on the under sides of said sub-frames, a plurality of spaced cutting discs carried by each of said other shafts, and driving means between each of said first mentioned shafts and said second mentioned shafts for rotating said second mentioned shafts and said cutting discs while said sub-frames are traversing the under side of said machine.

2. A road grooving machine having in combination a rectangular main frame, sub-frames mounted within the confines of said main frame, a threaded shaft for each sub-frame mounted on said main frame, a stationary threaded member mounted on each of said sub-frames, said threaded shafts engaging said stationary threaded members, means for rotating each of said threaded shafts so as to move each sub-frame from end to end of said main frame, a plurality of spaced cutting discs carried by each of said sub-frames, and means for rotating said cutting discs while each of said sub-frames are traversing the under side of said machine.

3. A road grooving machine having in combination a main frame, sub-frames mounted on said main frame, a threaded shaft for each sub-frame mounted on said main frame, a stationary threaded member mounted on each of said sub-frames, said threaded shafts engaging said stationary threaded members, means for rotating each of said threaded shafts so as to move each sub-frame from end to end of said main frame, a shaft extending from end to end of said machine for each of said sub-frames, means for rotating said shafts, other shafts mounted for rotation on the under sides of each of said sub-frames, a plurality of spaced cutting discs carried by said other shafts, and driving means between each of said first mentioned shafts and each of said second mentioned shafts for rotating said second mentioned shafts and said cutting discs while each of said sub-frames are traversing the under side of said machine.

4. A road grooving machine having in combination a main frame, a series of spaced cutting discs arranged transversely of said main frame, means for rotating said cutting discs, a pair of front wheels and a pair of rear wheels, means for driving a pair of said wheels so as to move the machine forwardly or rearwardly, said wheels

being mounted so that they may be swung at right angles to the position they occupy when the machine is moved forwardly or rearwardly so as to permit the machine to be moved in a lateral direction, and means for driving a pair of said wheels so as to move said machine laterally.

5. A road grooving machine having in combination a main frame, a series of spaced cutting discs arranged transversely of said main frame, means for rotating said cutting discs, a pair of front wheels and a pair of rear wheels, means for driving said rear wheels so as to move the machine forwardly or rearwardly, all of said wheels being mounted so that they may be swung at right angles to the position they would occupy when the machine is moved forwardly or rearwardly so as to permit the machine to be moved in a lateral direction, and means for driving one of said front wheels and one of said rear wheels so as to move said machine laterally.

10 15 20 25 30 35 40 45 50 55 60 65 70 75 80 85 90 95

6. A road grooving machine having in combination a main frame, a series of spaced cutting discs arranged transversely of said main frame, means for rotating said cutting discs, an auxiliary frame, a pair of front wheels and a pair of rear wheels carried by said auxiliary frame, means for driving a pair of said wheels so as to move the machine forwardly or rearwardly, said wheels being mounted so that they may be swung at right angles to the position they occupy when the machine is moved forwardly or rearwardly so as to permit the machine to be moved in a lateral direction, means for driving a pair of said wheels so as to move the machine laterally, and means whereby said main frame may be moved in relation to said auxiliary frame.

7. A road grooving machine having in combination a main frame, sub-frames mounted on said main frame, means for moving said sub-frames from end to end of said main frame, a plurality of spaced cutting discs carried by said sub-frames, means for rotating said cutting discs while said sub-frames are traversing the under side of said machine, a pair of front wheels and a pair of rear wheels, means for driving a pair of said wheels so as to move the machine forwardly or rearwardly, said wheels being mounted so that they may be swung at right angles to the position they occupy when the machine is moved forwardly or rearwardly so as to permit the machine to be moved in a lateral direction, and means for driving a pair of said wheels so as to move said machine laterally.

8. A road grooving machine having in combination a main frame, sub-frames mounted on said main frame, means for moving said sub-frames from end to end of said main frame, a plurality of spaced cutting discs carried by said sub-frames, means for rotating said cutting discs while said sub-frames are traversing the under side of said machine, an auxiliary frame, a pair of front wheels and a pair of rear wheels carried by said auxiliary frame, means for driving a pair of said wheels so as to move the machine forwardly or rearwardly, said wheels being mounted so that they may be swung at right angles to the position they occupy when the machine is moved forwardly or rearwardly so as to permit the machine to be moved in a lateral direction, means for driving a pair of said wheels so as to move the machine laterally, and means whereby said main frame may be moved in relation to said auxiliary frame.

HARRY TYSON.
